(57) CLAIM

The ornamental design for a tree step wrench section, as shown and described.

DESCRIPTION

FIG. 1 is a top view of a tree step wrench section embodying my design, the dotted lines showing an outline of the handle and shaft;

FIG. 2 is a top, front right side perspective view of the tree step wrench section as seen in FIG. 1;

FIG. 3 is a bottom plan view of the tree step wrench section as seen in FIG. 2;

FIG. 4 is a right side elevational view of the tree step wrench section as shown in FIG. 2;

FIG. 5 is a rear elevation view thereof; and,

FIG. 6 is a front elevational view of the tree step wrench section as shown in FIG. 2.

The broken lines shown in FIG. 1 are for illustrative purposes only and form no part of the claimed design.
